CLAIM

The ornamental design for a bottle opener, as shown and described.

DESCRIPTION

FIG. 1 is a perspective view of a bottle opener showing the new design;

FIG. 2 is a side view thereof, the other side views being identical thereto;

FIG. 3 is a top view thereof;

FIG. 4 is a bottom view thereof; and,

FIG. 5 is a cross-section thereof taken along the line 5-5 in FIG. 1.

The dash-dot lines shown in the drawing views are included for the purpose of showing environmental structure that forms no part of the claimed design. The dash-dot line in FIG. 4 represents a boundary of the claim on the bottom of the design.
